US00D939272S

(12) **United States Design Patent** (10) **Patent No.:** **US D939,272 S**
Benoit et al. (45) **Date of Patent:** **** Dec. 28, 2021**

(54) **FOOD PROCESSING ATTACHMENT**(71) Applicant: **WHIRLPOOL CORPORATION**,
Benton Harbor, MI (US)(72) Inventors: **Kaitlyn M. Benoit**, St. Joseph, MI
(US); **Michael P. Conti**, St. Joseph, MI
(US); **John Dykhouse**, Benton Harbor,
MI (US); **Timothy J. Hicks**, Berrien
Springs, MI (US); **Mitchell L.**
Robertson, Elkhart, IN (US)(73) Assignee: **Whirlpool Corporation**, Benton
Harbor, MI (US)(**) Term: **15 Years**(21) Appl. No.: **29/732,296**(22) Filed: **Apr. 23, 2020****Related U.S. Application Data**(63) Continuation of application No. 14/983,735, filed on
Dec. 30, 2015, now Pat. No. 10,820,735.(51) **LOC (13) Cl.** **31-00**(52) **U.S. Cl.**USPC ..... **D7/401.2**; D7/381; D7/384(58) **Field of Classification Search**USPC D7/372, 376-386, 401.2, 412, 665-666,

Primary Examiner — Ricky Pham

(74) Attorney, Agent, or Firm — Price Heneveld LLP

(57) **CLAIM**The ornamental design for a food processing attachment, as
shown and described.**DESCRIPTION**FIG. 1 is a front-right perspective view of a food processing
attachment according to the design;

FIG. 2 is a back-right perspective view thereof;

FIG. 3 is a front-right perspective view thereof showing the
food processing attachment mounted with an environmental
food processing device; and,FIG. 4 is a back-right perspective view thereof showing the
food processing attachment mounted with the environmental
food processing device.The portions of the article shown in even broken line form
no part of the claimed design.Dash-dot-dash broken lines are environmental only and
form no part of the claimed design.**1 Claim, 3 Drawing Sheets**# US D939,272 S
